RAZOR BLADE HOLDER FOR SHARPENING

Peter C. Rhegas, Detroit, Mich.

Application April 3, 1944, Serial No. 529,318

7 Claims. (Cl. 51—221)

This invention relates to an improved holder for a razor blade during honing.

This improved holder is adapted to support a razor blade, of the safety razor type, in such a manner that the beveled edge of the blade may be properly and accurately sharpened.

An object is to provide a holder which is simple and inexpensive and which will so support a blade, such as the thin wafer-type of blade, as for example a Gillette blade, that the honing operation may be properly carried out.

A further object is to provide a holder having a base which is adapted to support a razor blade of the character described with an edge portion of the blade projecting forwardly beyond the forward edge of the base and in a plane substantially parallel thereto whereby such portion of the blade will normally clear the surface upon which the base rests, but such portion is adapted to be resistingly depressed to bring its beveled edge to bear upon the surface upon which the base rests.

That portion of the blade projecting forwardly of the forward edge of the holder may be depressed manually to bring its beveled edge into bearing honing contact with the surface upon which the base rests. It may be depressed by direct pressure of the fingers of the operator thereagainst or depressing means may be provided which means is adapted to bear against the blade adjacent to its forward edge and forwardly of the holder to urge such forward beveled edge of the blade against the surface upon which the blade rests. Such depressing means is adapted to urge the beveled edge of the blade throughout its length against the honing surface.

A large number of devices have been developed to support the wafer-type of safety razor blade to sharpen the blade. One difficulty attending the sharpening of a blade of this type is to so support the blade at all times during the honing operation that it will be accurately sharpened. It is not an uncommon disadvantage present in many of these prior art devices that a blade may be properly supported at one time and improperly supported at another time and the particular manner in which the blade support is held by the operator may determine whether or not the sharpening operation is properly carried out.

One object of this invention is to provide a device wherein a blade supported thereby will always be so supported that the sharpening operation will be properly carried out. This improved holder is adapted to rest flat upon a honing sur-

face and to be moved back and forth across such surface during the sharpening operation. The honing surface may be of any desired character. The blade carried by the holder is so supported that when it is urged at such an angle thereto that the forward beveled edge only of the blade will be brought into honing contact with the surface. The device is so constructed and so proportioned as to insure the accomplishment of the above end.

The construction is such that the holder may be moved back and forth over a flat honing surface with the base resting flat upon such surface and the beveled edge of the blade may be resistingly depressed against such honing surface in one direction of movement of the holder thereto while in the opposite direction of movement of the holder the forward edge of the blade may be released to assume a normal position of parallelism with the base and clear the honing surface.

Other objects, advantages, and meritorious features will more fully appear from the description, appended claims, and accompanying drawings wherein:

Fig. 1 is a plan of device embodying the invention showing the razor blade mounted thereon.

Fig. 2 is a transverse sectional view taken on the line 2—2 of Fig. 1.

Fig. 3 is a sectional view taken on the line 3—3 of Fig. 2.

Fig. 4 is an enlarged sectional view through a fragment of the holder showing the forward portion of the blade depressed.

Fig. 5 is a fragmentary sectional view taken on the same line as Fig. 4 illustrating a modified form of construction.

Fig. 6 is a sectional view taken on the same line as Fig. 2 but illustrating a modified form of structure.

Fig. 7 is a fragmentary plan taken on the line 1—1.

This improved holder comprises a flat base 10 provided with upstanding side walls 12 which serve as a handle or finger gripping portion. In Figs. 1, 2 and 3 this base is shown as consisting of an upper layer and a lower layer of material which layers may be formed of sheet metal or any other suitable material. The lower layer is folded over the upper layer at the rear end as shown at 14 for securing thereto. It is apparent that the base might be formed of a single sheet of material.

A blade holding lug 16 extends upwardly from the base adjacent to its forward edge. This lug

or part is adapted to be received through the linear slot formed in a razor blade 18. In Figs. 1, 2 and 3 such a blade 18 is shown as supported flat upon the base engaged over the lug 16 and projecting forwardly of the forward edge of the base as shown particularly in Fig. 2. In Figs. 1, 2 and 3 the lug is shown as extending rearwardly as well as upwardly so as to tend to hold the blade down against the base when the blade is urged forwardly over the base against the lug. 10

Blade depressing mechanism in the form of a yoke-like element 20 is pivoted at 22 to the side walls 12. This yoke-like element has a flat front portion 24 which is of a length to extend throughout the length of the blade adjacent and parallel to its front margin as shown in Figs. 1 and 2. The arms of this yoke 20 lie flat across the upper surface of the blade at the ends as shown in Fig. 2 to hold the blade flat against the base. These arms are flexible to permit of the forward portion 24 of the yoke being depressed to urge the edge of the blade against the honing surface 32. 20

In Figs. 4 and 5 there is shown a slight modification of the structure illustrated in Figs. 1 through 3. In these figures the lug 16 projects upwardly vertically from the base instead of extending slightly rearwardly as shown in Figs. 1 and 2. 25

In Figs. 6 and 7 there is illustrated a second modification. The base is indicated as 18. It is provided with side walls 12 and with an upwardly projecting lug 16 adapted to engage a blade 18 to support the blade to project forwardly of the forward edge of the base in a manner similar to that hereinabove described. This 30 particular base is also shown as formed of two thicknesses of sheet metal and the folded over edge 14 of the outer thickness receives thereunder, as illustrated in Figs. 6 and 7, a spring element 30. This spring element is adapted to engage the rear portion of the blade to hold the same yieldingly downwards against the base as shown in Figs. 6 and 7. 35

Fig. 4 shows the front portion 24 of the pivoted yoke 20 as being swung downwardly depressing the blade so as to bring the forward beveled edge of the blade into engagement with the honing surface 32 upon which the base rests. An operator may grip the side walls 12 of the base with one hand and with one or more fingers urge the front portion 24 of the yoke downwardly to bring the beveled edge of the blade into honing contact with the surface 32. The arms 30 of the yoke serve to hold the blade flat against the base as shown in Figs. 2 and 4. 40

Inasmuch as the portion 24 of the yoke 20 has a length equal to the length of the blade and engages the blade adjacent to its forward beveled edge, the blade is held against the honing surface throughout its length evenly and properly. 45

In Figs. 5, 6 and 7 the forwardly projecting portion of the blade may be urged down against the honing surface 32 through direct pressure of the fingers thereagainst as shown in Fig. 5. The spring member 30 tends to hold the rearward portion of the blade flat against the base. In the structure shown in these figures, a blade which is relatively inflexible might be sharpened through the blade being permitted to tilt against the resistance of the spring 30 to bring its forward edge into proper contact with the honing surface. Tilting to bring the forward edge into honing engagement instead of flexing for the same purpose is an alternative method of operation. 50

The thickness of the base and the position of the blade engaging lug is such that when a razor blade is supported upon the base and engaged by the lug, one edge portion of the blade projects forwardly beyond the forward edge of the base such a distance that when such edge portion is depressed toward the surface upon which the base rests it will contact such surface along its beveled edge only. Normally the blade when not depressed projects forwardly beyond the forward edge of the base in a plane parallel to the plane of the base and spaced above the surface upon which the base rests a distance equal to the thickness of the base. 55

One preferred method of operation is to move the holder forwardly and backwardly along a line parallel to the section line 2—2 and hold the blade down in honing contact with the surface 32 during its rearward movement and to release the downward pressure of the fingers therefrom during the forward direction of movement. Upon release of this downward pressure the forward portion of the blade will spring upwardly to the position shown in Fig. 2 so as not to burr up the edge of the blade as it is moved forwardly. 60

The base is preferably shown as formed of two thicknesses or layers of material which are separable at the forward edge. Though as heretofore stated it might be formed of a single thickness of material. With two separable thicknesses it is possible to preserve during use the proper thickness of base to insure the beveled edge of the blade being properly urged against the flat honing surface. A thin shim 13 of any suitable substance may be inserted between the lower layer and the upper layer at the forward edge to take up for wear of the bottom face of the lower layer. Such shim is shown in Fig. 2 of the drawing and it is apparent that it might be inserted between these two layers at the forward edge of the base by spreading these layers apart and that shims of varying thickness might be used. 65

What I claim is:

1. A sharpening device for holding a razor blade during honing comprising a flat plate like base provided with a finger gripping portion and with a blade positioning part, said base having a flat bottom surface adapted to rest flat upon a honing surface and having a flat upper surface portion of a length to support a razor blade throughout its length and adapted to support said razor blade engaged with said part and projecting forwardly beyond the forward edge of the base and with the forwardly projecting portion normally occupying a plane parallel to the plane of the base and spaced above the flat surface upon which the base rests, said forwardly projecting portion of the blade adapted to be depressed to bring its beveled edge adjacent to its forward margin into honing contact with the flat surface upon which the base rests. 70

2. A sharpening device for holding a razor blade during honing comprising a flat plate like base provided with a finger gripping portion and a blade positioning part, said base having a flat bottom surface adapted to rest flat upon a honing surface and having a flat upper surface portion of a length to support a razor blade throughout its length and adapted to support a razor blade engaged with said part and projecting forwardly beyond the forward edge of the base and with the forwardly projecting portion spaced above a flat surface upon which the base rests and occupying a plane parallel to the plane of the 75

base, said base having such a thickness compared with the thickness of the blade and with the forward projection of the blade beyond the base that upon depression of the forwardly projecting portion of the blade throughout a distance equal to the thickness of the base the beveled edge of the blade is brought into honing contact with the flat surface upon which the base rests adjacent only to the outer margin of said beveled edge.

3. A sharpening device for holding a razor blade during honing comprising a flat plate like base provided with a finger gripping portion and with an upwardly projecting blade positioning part, said base having a flat bottom surface adapted to rest flat upon a honing surface and having a flat upper surface portion of a length to support a razor blade throughout its length and adapted to support a razor blade engaged with said part and projecting forwardly beyond the forward edge of the base and with said forwardly projecting portion spaced above a flat surface upon which the base rests and occupying a plane parallel to the plane of the base, and depressible means secured to the base engaging the blade spaced forwardly beyond the forward edge of the base and depressible to urge the forward beveled edge of the blade into honing contact with the surface upon which the base rests.

4. A sharpening device for holding a razor blade during honing comprising a flat plate like base provided with a finger gripping portion and with a blade positioning part, said base having a flat bottom surface adapted to rest flat upon a honing surface and having a flat upper surface portion of a length to support a razor blade throughout its length and adapted to support a razor blade positioned by said part projecting forwardly beyond the forward edge of the base and with the forwardly projecting portion spaced above a flat surface upon which the base rests and normally occupying a plane parallel to the plane of the base, said device provided with blade depressing means having a part adapted to bear against the blade throughout its length and adjacent and parallel to the forward edge of the blade, said means adapted to be depressed to urge the beveled forward edge of the blade uniformly throughout its length against the flat surface upon which the base rests.

5. A sharpening device for holding a razor blade during honing comprising a flat blade supporting base provided with upwardly projecting finger gripping side walls and provided with a blade engaging part projecting upwardly and rearwardly of the base adjacent to the forward edge thereof, said base adapted to support a razor blade engaged with said part and with the blade

projecting forwardly beyond the forward edge of the base and with the forwardly projected portion of the blade spaced above a flat surface upon which the base rests by a distance equal to

5 the thickness of the base, blade depressing means pivotally supported between said side walls and having a blade engaging portion adapted to engage a blade throughout its length and adjacent to its forward margin and spaced forwardly beyond the forward edge of the base, said means being swingable to depress the forwardly projecting portion of the blade to bring its forward beveled margin into honing contact with the surface upon which the base rests.

10 6. A sharpening device for holding a razor blade during honing comprising a base provided with a finger gripping portion and a blade positioning part adapted to engage a blade supported upon the base with the blade projecting forwardly beyond the forward edge of the base in a plane

20 extending substantially parallel to the plane of the base and with the forwardly projecting portion of the blade spaced above the surface upon which the base rests by the thickness of the base, said forwardly projecting portion of the blade adapted to be depressed to urge the edge of the blade against the surface upon which the base rests, said base consisting of an upper and a lower thickness of material and means being provided for spacing said two thicknesses of material apart underneath the blade to adjust the thickness of the base below the blade.

7. A sharpening device for holding a razor blade during honing comprising a flat plate like base provided with a finger gripping portion and with a blade positioning part, said base having a flat bottom surface adapted to rest flat upon a honing surface and having a flat upper surface portion of a length to support a razor blade throughout its length and adapted to support a razor

40 blade positioned by said part projecting forwardly beyond the forward edge of the base and with the forwardly projecting portion spaced above a flat surface upon which the base rests and normally occupying a plane parallel to the plane of the base, said device provided with blade depressing means having a part adapted to bear against the blade throughout its length and adjacent and parallel to the forward edge of the blade,

45 said means adapted to be depressed to urge the beveled forward edge of the blade uniformly throughout its length against the flat surface upon which the base rests, said blade depressing means having a flexible part extending transversely of the blade and bearing thereagainst and holding that portion of the blade resting upon the base flat against the base.

PETER C. RHEGAS.
